W. M. SCHOLL
METATARSAL ARCH SUPPORT

1,767,263

Filed Dec. 1, 1924

UNITED STATES PATENT OFFICE

WILLIAM M. SCHOLL, OF CHICAGO, ILLINOIS

METATARSAL ARCH SUPPORT

Application filed December 1, 1924. Serial No. 753,330.

The invention relates to orthopaedic appliances for correcting malformed feet.

The device is especially applicable for supporting the metatarsal bones of the feet to maintain the normal metatarsal arch.

Many adults suffer from the results arising from depressed or fallen metatarsal arches due to the weakening and elongation of the ligaments which normally support and hold the metatarsal bones in their normal healthy positions. Frequently other complications set in after a protracted time until the joints are permanently dislocated and displaced. The superimposed weight of the unfortunate person causes undue and excessive pressure upon the displaced parts of the foot which produces callouses of the feet. Toes are sometimes dislocated and bunions appear as a result of the fallen arch, weak ankles, elongated feet and loss of poise may result.

One of the objects of the invention is to provide an improved device, or foot appliance, which will transversely contract the forepart of the foot and support the displaced parts thereof in their natural position.

Another object is to provide an improved arch support having means to individually support either of the five metatarsals of the foot and rotatably shiftable, transversely of the foot, whereby the support may be located under any part of the foot within its shiftable path to elevate and hold any one of the metatarsal bones elevated in its natural position.

Another object is to provide an arch support to be held in place by a flexible band and having an insertable pad held in place within a pocket thereof, by said band.

Another object is to provide an arch support having a pocket within which to insert the pads and which is closed, fore and aft, by stitching or otherwise, and having a side opening only, which side opening is closed by said band after the pads have been inserted.

Other objects and advantages of the invention will appear to the person skilled in the art from the description when taken in conjunction with the drawings, wherein:

Figure 1 is a side elevation of the device showing the band reversed to make the open-

ing in the pocket accessible for the insertion of pads.

Figure 2 is a side elevation of the device with the band in its normal position, showing the pocket closed by the band.

Figure 3 is a section taken on line 3—3 of Figure 2.

Figure 4 is a section taken on line 4—4 of Figure 5.

Figure 5 is a plan view of the device, showing one place of the pocket structure broken away.

Figure 6 is a bottom plan view of a foot showing the device in position thereon.

In all the views, the same reference characters are used to indicate similar parts.

The part which extends around transversely of the foot consists of a rubber bandage 10, made of an elastic fabric or strip joined together end to end as at 11, and 11', making the seam 12, between the ends 11 and 11', by which the parts are held in the same plane. The object of this is to prevent double thickness of the band which would make a hump to the discomfort of the wearer.

The pocket structure 14 consists of two plate members 15 and 16 of relatively stiff material with respect to the character of the bandage or band 10 and are preferably made of leather or the like. The fore-and-aft edges 17 and 18 of the pocket structure are held together as by stitching 19, and the side edges are left open, whereby to construct a pocket with the opening of the pocket being along the side edges, or one thereof, instead of being at either end. The band 10 is sewed to the pocket member 16 by stitching through the center of the seam 20 which holds the ends 11 and 11' together. A piece of material 21 substantially as flexible as either of the plate members 15 and 16 and substantially as thick as the band or bandage 10, is placed in front of the bandage so that the parts underlining the plate 15 will be substantially of uniform thickness.

In the pocket, between the members 15 and 16, is insertable a cushion or pad 22 to raise the member 15, to a greater or less extent, to provide an arch support for elevating and

holding the metatarsals of the foot in their natural positions.

In Figure 6, the device is shown as applied to the bottom of the foot. It is manifest that it may be shifted laterally from the position shown, to be located under another affected part of the foot. One or more pads 22 may be inserted in the pocket and they may each be of any thickness desired or shaped in form 10 for the requirements of the foot. In Figure 1, two pads are shown in the pocket, while in Figures 3 and 4, only one pad is shown therein.

The pocket, formed of the plate members 15 15 and 16, is open at its side edges, or at least one edge thereof, and closed at its end edges. One object of this is to prevent the pads from leaving the pocket. In the position which the parts occupy when ready for use, the 20 bandage 10 substantially closes the pocket as shown in Figures 2 and 3, so that the pads may not unintentionally be removed from the pocket.

Figure 1 shows the bandage reversed; that 25 is, turned to the opposite side of the pocket structure. This opens the pocket for the insertion of the pads. After the pads have been inserted, the bandage is returned to its normal position, as shown in Figures 2 and 3. 30 This closes the pocket and the device is then ready to be applied to the foot.

Having described my invention, what I claim as new and desire to secure by Letters Patent is:

35 1. A foot corrective appliance comprising a bandage to be applied transversely about the foot; and a pocket structure secured to the bandage, said structure comprising an upper pocket member lying on the inner side 40 of the bandage and a lower pocket member lying on the outer side of the bandage to which said bandage is attached, said members being secured together across their ends, leaving the parts open between their side 45 edges to form an open pocket, said opening being normally covered by said bandage.

2. A foot corrective appliance comprising an elastic, closed band to be applied transversely about the foot; and a pocket structure comprising two relatively stiff plate members, one on each side of said bandage, said members secured together across their ends, leaving said members disconnected 50 along their side edges and covered by said band whereby said pocket is substantially 55 closed by the band.

3. A foot corrective appliance comprising an elastic bandage to be applied to the foot 60 formed of a band stitched across its ends, with its ends in the same plane; a pocket structure, comprising two relatively stiff plate members, said bandage secured to one of said plates by stitching between the ends of the 65 bandage, the other plate registering with the

first plate and overlying the bandage, and means securing the ends of the plates together to form a side open pocket, sewed to the bandage, and into which to insert a pad.

4. A foot corrective appliance comprising 70 an elastic bandage to be applied to the foot; a pocket structure comprising two relatively stiff plates, one on each side of said bandage, and one being secured to the bandage; means to secure the end edges of the plates together to form a side-open pocket normally closed by said bandage, and a tapered pad insertable in said pocket.

5. A foot corrective appliance comprising 75 an elastic bandage to be applied to the foot formed of a band joined together at its ends; a pocket structure comprising two relatively stiff plates projecting fore-and-aft of said bandage and enclosing the joined ends thereof, one of which plates is directly connected to said bandage; means connecting the ends of the plates together to form an open pocket between the side edges of said plates, said pocket being closed by said bandage by overlying one of said plates, and a pad insertable into said pocket when the said band is turned over the other plate.

6. In a device of the class described the 80 combination with an endless elastic band of a pad holder comprising a pocket like structure having openings along two opposite edges thereof, the band passing through said openings and being secured centrally of the inner wall of one of the sides of the pad holder and a pad insertible in the pad holder through one of the openings therein.

7. In a device of the class described the 85 combination with a pad holder comprising a pair of side pieces secured upon one another along the edges thereof and having openings 90 along two of its opposite edges of an elastic band disposed between the sides of the pad holder and secured upon the inner wall of one of said sides along a line extending longitudinally of said side and a pad insertible 95 between said sides through one of the openings in the pad holder.

8. In a device of the class described the 100 combination with a pad holder comprising a pair of sheets of flexible material secured upon one another upon their forward and rear edges whereby an opening is provided therethrough, the opening extending transversely of said holder, an elastic band extending through the said transverse opening in the pad holder, and a pad carried between the 105 flexible sheets.

9. In a device of the class described the 110 combination with a pad holder comprising a pair of sheets of flexible material secured upon one another upon their forward and rear edges whereby an opening is provided 115 therethrough, the opening extending transversely of said holder, an elastic band extending through the said transverse opening 120 in the pad holder, and a pad carried between the flexible sheets.

in the pad holder, a pad carried between the flexible sheets, and means for attaching the elastic band to one of the said flexible sheets.

10. In a device of the class described the combination with a pad holder comprising a pair of sheets of flexible material secured upon one another upon their forward and rear edges whereby an opening is provided therethrough, the opening extending transversely of said holder, an elastic band extending through the said transverse opening in the pad holder, a pad carried between the flexible sheets, and means for attaching the elastic band to one of the said flexible sheets,
- 15 said means being arranged to secure the band to said flexible sheeting longitudinally of the pad holder and leaving the lateral edges of the elastic band free whereby all the elasticity of the band may be utilized.
- 20 11. In a device of the class described the combination with a pad holder comprising a base and a sheet of flexible material secured upon one another upon their forward and rear edges whereby an opening is provided therethrough, the opening extending transversely of the said holder, an elastic band extending through the said transverse opening in the pad holder, a pad carried between the base and flexible sheet and means
- 25 for attaching the elastic band to the base along a line extending longitudinally of the pad holder, thereby leaving the lateral edges of the elastic band free for utilizing all the elasticity of said band.
- 30 35. In testimony whereof I have hereunto subscribed my name.

WILLIAM M. SCHOLL.
